REGULATING SYSTEM FOR HYDRAULIC TURBINES

Application filed January 7, 1929. Serial No. 527,544.

This invention relates to hydraulic power systems and particularly to a regulating system for a power station in which there are a number of turbine units driving electric generators or similar apparatus, especially a power station in which a number of the turbines drive alternators running in parallel. The object of the invention is to provide a regulating system in which a plurality of separate turbines will have a unified control governing the speed and power of the various units in coordination with each other.

In prior practice where there are a number of turbines it has been usual to provide each unit with a separate governor adapted to adjust the turbine gates independently according to the speed fluctuations of its individual unit. Thus the regulation of each unit is separate and independent of the others. In such a system the large number of complete governors required are expensive in first cost and upkeep and complicated in mechanism, and require delicate relative adjustments between the various governors to maintain proper distribution of the loads among the various units. The fluid pressure piping and pumping systems to supply a large number of governors are complicated and expensive. Whenever one governor is disabled, its corresponding unit is either out of operation or left to hand-control.

In the regulating system of this invention, this multiplication of separate governors is avoided and a means is provided whereby a limited number of governors are adapted to exercise a combined control over all the units; at the same time simplifying the regulating mechanism and reducing the cost of installation and maintenance.

Further objects of the invention, particularly in the adaptation of the system to units having different regulating characteristics so as to effect still further economies in structure and operation will appear from the following description taken in connection with the accompanying drawings in which,

Fig. 1 is a diagrammatic elevational view of a turbine system embodying the invention,

Fig. 1a is a modification of a detail of Fig. 1,

Fig. 2 is a view similar to Fig. 1, showing a modification,

Figs. 3 and 4 are diagrammatic plan and elevational views respectively of another embodiment of the system of this invention shown on somewhat enlarged scale,

Fig. 5 is an enlarged detail view of portions of the apparatus shown in Figs. 3 and 4, and

Figs. 6, 7 and 8 are diagrammatic sectional views of details of the apparatus used in the system of Figs. 3 and 4.

The specific embodiment of the invention as diagrammed in Fig. 1 comprises a series of turbine units $T_1, T_2, T_3, \dots$, each of which drives an alternating current generator E and has wicket gates G controlling the flow to the turbine runner R . The units are shown substantially similar and the alternators E are in parallel and in synchronism with each other and share the load on the line. One of the turbine units T_1 has an automatic speed governor 15 driven from the turbine and acting to control the gates G to vary the power supply according to the load. The governor mechanism of unit T_1 , as here shown, is arranged in a novel manner to secure the unified control of a number of units, as will be explained. The governor head 16, which may be of the usual centrifugal flyball type or equivalent device performing the same functions, as for example an electrical device, moves the central pin of the floating lever 16 vertically in proportion to the speed of the unit. During quick load changes on the unit, the left-hand end of the floating lever 16 is held nearly stationary by the vertical rod 17 and the dashpot 18. The right-hand end of the floating lever moves the rod 19, which carries a pilot valve (not shown) acting within the cylinder 20. Within the cylinder 20 is a piston actuating the vertical rod 21. The cylinder and piston 20 form a relay device; the pilot valve works within the piston, so that any motion of the pilot valve is instantly copied by the piston through the admission and exhaust of fluid pressure to the ends of the cylinder 20. By this means the rod 21 is moved with considerable power.

by means of the fluid pressure and this rod is used to operate the valves, which move the grates not only of unit T_1 , but also of the other units under the control of this governor. This is accomplished as follows:

- 8 The rod 21 imparts its motion to the horizontal interconnecting rod 30 which interconnects the units of this regulating system. In any unit, such as T_1 , the motion of the interconnecting rod 30 actuates through a bell crank 22', link 21' and lever 26' the stem 23' of the main control valve of this unit, which is contained within the valve casing 34'. The main control valve of unit T_1 is simultaneously actuated in an exactly corresponding manner through the rod 21, lever 26 and the valve stem 23. Rod 30 can be arranged in a duct or tunnel. In large units, stem 23 (23') can be arranged 10 to operate valve 34 (34') through a relay.
- 15 Interposed in the mechanism which transmits the motion of rod 21 and interconnecting rod 30 to the main control valve of each unit is a compensating or restoring mechanism connected to the turbine gates through the gate operating mechanism. This restoring mechanism takes its motion 20 from the operating piston rod 25 of the turbine through the bell crank 24 and moves the left-hand end of the floating lever 26, 26' an intermediate point of which is actuated by the rod 21, 21' and the right-hand end of which moves the valve stem 23, 23'. Whenever a change of speed occurs in the 25 unit, the motion of the governor head causes rod 21, 21' to take a new position corresponding to the new speed. This moves the floating lever 26, 26' about its left-hand end as a fulcrum and causes valve 23, 23' to admit 30 fluid pressure to the turbine operating cylinder 27, 27' and moves the turbine gates. The motion of the gates in turn is transmitted through the restoring mechanism to the left-hand end of the floating lever 26, 26' and restores the valve 23, 23' to its neutral or mid-position. Thus the turbine gates of all the units repeat the motion of the rod 21, and when they have reached a position corresponding to that of rod 21, they remain in that position until there is any further change in the speed of the unit.

The governing action so far described is, however, not complete. Assuming that the speed of the first unit has ceased changing, the unit is operating in an equilibrium between its power and load and the gates are for the moment stationary. This condition of equilibrium will however in general be obtained when the speed has considerably 40 changed from the normal operating speed which it is desired to maintain in all the units in the system. In order to restore the speed of the units to normal, a secondary compensating mechanism is provided in the governor proper. This secondary compensation

readjusts the rod 21 by giving it an additional movement in the same direction as its initial movement and thereby restores the speed to the desired normal value. This secondary compensating motion must in hydraulic plants take place at a sufficiently slow rate to avoid introducing disturbances in speed or hunting which would result, if it were endeavored to accelerate or retard the water column in the turbine water passages too quickly. The necessary slowness of operation of this secondary compensation is secured by means of the dash-pot 18 and the secondary floating lever 28 of the governor. The spring 29 controls the motion of this secondary floating lever and exerts a force tending to restore the intermediate point of this lever to a fixed position. After any motion of rod 21 due to a quick change in speed, floating lever 28 will at first fulcrum about its left-hand end and the spring 29 will be either compressed or extended. The action of this spring will slowly move the rod 17 under the control of the dash-pot 18. This slow motion of rod 17 will be transferred through the floating lever 16 which now fulcrums about its intermediate point of connection to the governor head, and will readjust rods 19 and 21, giving the gates of all of the inter-connected units a simultaneous additional motion in the same direction. This motion will continue until spring 29 has reached its normal position and the speed has been fully restored to normal value.

It will be noted that the compensating motions have been separated into two mechanisms—one, the primary restoring mechanism, being arranged to operate separately on the main control valve of each unit, and the secondary compensating mechanism being arranged as part of the governor proper so as to act in common on all of the units simultaneously. This arrangement of governor mechanism will have advantages even when applied to an individual unit without the interconnecting system, since it enables short primary restoring connections to be used between the main control valve, which may be located close to the turbine operating cylinders, and the gate mechanism of the turbine. In some cases, it will be desirable for the bell crank 24 to be directly connected to the operating ring of the gate mechanism instead of to the operating piston rod. The secondary compensation can according to this arrangement be made a standard and integral part of the governor proper and can be self-contained within it, and no restoring connection is necessary between the governor proper and the turbine.

When the above arrangement is applied as described to a number of units, the control of the gates of the various units is simultaneous, and there is no tendency of the gates of any one unit to move in advance of the

others. The alternating current generators E are in step with each other and during normal operation the various units will be automatically maintained at equal speeds by the electrical forces tending to hold them in synchronism. A number of alternators thus running in step have the same speed and a separate centrifugal fly ball device responsive to the speed of each individual unit may be dispensed with, and as long as the plant remains in proper operation the centrifugal governor responsive to the speed of any one unit is sufficient to regulate the plant.

In order to enable the load to be accurately distributed among the units, the hand-wheel 31 is provided, which may be mounted on the hand-operating stand of each unit, or at other convenient point. This hand-wheel adjusts the point of connection between the left-hand end of floating lever 26 and the primary restoring mechanism. This hand-wheel adjustment enables the gate opening of any unit to be altered while still leaving the unit under the control of the regulating system described above. In addition to this hand-adjustment, each unit will when desired be equipped with the usual hand-operating stand 32 containing a hand controlled valve for the fluid pressure to operating cylinder 27, 27' by which the unit may be placed under hand-control independently of the regulating system described above whenever it is desired to remove the control of the unit from the regulating system.

It will be understood that Fig. 1 is only diagrammatic and does not show either the complete details of the mechanism or the exact proportions which would be used in a given installation. For example, bell cranks 22 and 24 need not in general have equal arms, as shown, and the point of sub-division of floating lever 26 would be subject to change; it might even be desired in some cases to interchange the points of connection of rods 21 and 23. It should also be mentioned that the point of connection of spring 29 to floating lever 28 will usually be made adjustable, and the fixed end of spring 29 will also be adjustable to adjust the speed of the units.

In many installations it will be desirable to install more than one governor, so that a governor 15 may be taken out of operation for inspection or repair while the system is under the control of another governor 15' (Fig. 1a). This may be done by arranging the upper portion of rod 21 of each governor so that it may be disconnected from the bell crank 22, as shown, leaving the governor so disconnected out of operation, and the gates under the control of the interconnecting rod 30 connected to another governor. The control can thus be taken by any one governor by connecting up rod 21. As indicated in Fig. 1a it may be desirable instead of connecting both of the governors to the control rod to

connect them first by rods 41 to a differential equalizer 42 so that the control rod 30' will be actuated and controlled by the average gate position of a plurality of governed units T, T.

The above system of regulation is well adapted for use in a station having a relatively small number of units, each of which is equipped with an individual governor. In such plants, it will frequently be desirable to install the interconnected system described, so that any one unit may, when desired, be removed from the control of its governor and placed under the control of the governor of another unit by the use of this system.

The system of this invention as above set forth effects a substantially simultaneous movement of the gates of all the units so that all the flows are varied together and to approximately the same extent. It will, however, prove advantageous in many installations to adapt certain of the units for relatively slow regulation and to depend upon the remaining few to follow the load variations quickly. This in some cases may be used to further simplify design and the water passages of the slowly regulated units may be made smaller; and smaller piping for the operating pressure may be used for all of these units. The penstocks and water passages may be reduced in size as higher velocities of flow are permissible where the rate of change of flow is reduced, and this further permits of a closer spacing of these units and a saving in the overall size of the power house.

Such a system is particularly applicable to many modern installations where the fluctuations of load which must be carried by the station are small in comparison with the total output of the station. A large proportion of modern installations are interconnected with extensive systems and the load in such systems is usually extremely steady. The load variations which must be taken care of by the governors during normal operation are in many cases well within the capacity of a single unit. In the station forming a part of a large modern system therefore it often happens that the amount of load variation to be cared for by the station is not great enough to require the equipment of every unit with a separate governor. In such case it will be advantageous to provide a station with a limited number of units having the usual wicket gates and equipped with governors. The number of these units is to be determined by the fluctuations in load which are expected to be imposed on the plant during operation and this will depend upon the character of the system which the plant is supplying and the nature of the load; the remaining units in the station may then be built of a different type less adapted to quick regulation but offering the best solution when freed from the restric-

tion of regulation requirements. For example, in a low head plant it will frequently be desirable to adopt for these secondary units turbines of the plunger gate type or other type having a relatively simple operating mechanism designed only for slow gate motion. Figure 2 shows a system of regulation for such a plant, having a portion of the units under primary or quick-acting governor control, and the other units under secondary or slowly-acting control.

In the system illustrated in Fig. 2, the turbine unit T' is of the wicket gate type and the remaining turbine units t are of a more slowly regulating type, having plunger gates g , moved axially by fluid pressure to control the flow. The regulating mechanism of the turbine T' is connected by rod 50 to the regulating means of the remaining units t so that the whole system is controlled from the governor 45 of the turbine T' . This interconnecting and regulating mechanism is shown on larger scale in Figs. 3 to 6 in connection, however, with turbine units of the wicket gate type instead of the plunger gate type outlined for the units t in Fig. 2. The principle of operation is the same in either case. The governor 45 of turbine T' has a rod 46 acting through intermediate relay mechanism to control the fluid pressure in operating cylinder 55 of the turbine gates G' . Restoring connections are provided between the gate operating mechanism and the governor and these comprise a bell crank 52, linked to the piston rod of the cylinder 55 at one end and to the bell crank 53 at the other end. The vertical arm of bell crank 53 in turn is linked to the interconnecting rod 50 so that the latter partakes of the movement of the gates G' .

The method of control of the Fig. 2 arrangement will in general be particularly suitable for low head plants, and especially those having a large number of units. In certain installations, especially those comprising a small number of units of large capacity, still another arrangement of the units may be advantageously adopted, employing the method of regulation of this invention. The arrangement referred to comprises the use of two different types of gates in an individual turbine; one type of gate being employed for quick regulation to care for the usual load variations to which the plant is subjected, and the other type of gate being used for a slow adjustment under the secondary method of control described herein. For example, one or all of the units could be equipped with both wicket gate and plunger gate control, the wicket gates being operated by the governor and the plunger gates by the secondary system of control. By this arrangement, it will in general be unnecessary for the wicket gates to be capable of closing completely, or of controlling the load

throughout the entire power range of the unit; a small number of wicket gates could be used, widely spaced around the intake of the runner, thus reducing both the hydraulic friction of the gate surfaces and the hydraulic load which the operating mechanism must handle. For complete closure, or for handling large load changes, the plunger gate would be operated by the secondary control; for quick fluctuations, the wicket gates would operate under governor control. After any quick change in the position of the wicket gates corresponding to a change in load, the plunger would under the influence of the secondary control system slowly follow up the motion of the wicket gates until both the wicket gates and plunger gate have automatically adjusted themselves to corresponding degrees of opening. This system of control is equivalent to that shown in Fig. 2 as applied to a number of separate units; but in the arrangement just described the different types of gates instead of being in different units are applied to the same unit.

In the system shown in Figs. 3 and 4 as in Fig. 2 unit T' to the left is a primary controlled unit and the unit T'' to the right is one of the secondary controlled units regulated by connection of its operating means to the gate mechanism of the primary unit. These secondary units T'' are each provided with a special operating stand h and connecting mechanism capable of moving the corresponding gates at a slow rate compared to the gate motion of the first unit. This mechanism and control stand are shown on a larger scale in Fig. 5 which indicates the secondary control. In this figure will be seen the horizontal interconnecting rod 50 which continues to the right for the operation of the remaining secondary units in the station. This rod 50 is connected by a bell crank 56 with a vertical rod 57 running upward into the base of the control stand h . This rod 57 is connected to a horizontal floating lever 58 shown by dotted lines. The left hand end of this floating lever 58 is connected to a similar vertical rod 59 which runs downward to the large bell crank 60 linked to the operating piston 61 of the unit. The center of the floating lever is connected to and actuates the stem 62 of a fluid pressure valve 63 contained in the upper portion of the control stand h (Fig. 6).

The structure of this valve and mechanism of stand h is shown in enlarged sectional view in Fig. 6. The valve 63 is of the balanced piston type which when moved upward connects the pressure port 64 to one end of the cylinder 55 through port connection 65 to close the turbine gates, the other end of the cylinder 55 being simultaneously connected to exhaust through ports 66 and 67. Downward movement of the valve 63 reverses the pressure and exhaust connections

to reverse the movement of the gates toward open position. The valve stem 62 passes through the valve and is screw threaded therein at 68 and swiveled in the lever 58 at 69 and provided with a hand wheel 70 so that the valve 63 may be moved either by vertical movement of the stem 62 or by rotational movement of the stem 62 when turned by the hand wheel 70.

Assuming the gates of the turbines to be at rest at any given moment, a change in the station load will cause the governor 45 of the primary unit to operate to move the gates G' of the primary unit T' and these in turn will move the horizontal interconnecting rod 50. The effect of this will be to raise or lower the right hand end of each floating lever 58, the left hand end of this lever being held stationary by its restoring rod connection to the gates of the corresponding unit. The middle of the lever 58 will move the valve stem 62 with a motion corresponding to that of the interconnecting rod 50. This motion will open the hydraulic piston valve 63 admitting pressure to one end or the other of operating cylinder 55 or to one side of the plunger of a plunger gate turbine. The admission of this pressure will then cause a shifting of the gates g' of the secondary units, which in turn will be communicated to the left hand end of the floating lever 58 and when the gates g' have moved an amount corresponding to the motion of the interconnecting rod 50 the valve 63 will be restored to midposition. This gate motion of the secondary units T' will take place at a definitely restricted rate sufficiently slow so as not to interfere with the regulation of the primary unit T' . This restriction may be caused by a limited port area of the valve and a limited size of piping leading to the operating cylinder or operating plunger in case plunger gate turbines t are used.

The action just described will cause the gates g' of the secondary units to follow up the gate motion of the primary unit T' and take up a corresponding position, so that after the secondary controlling motion is completed all the units will be at substantially the same or a corresponding gate opening, provided, of course, that no further change of load has in the meantime occurred. While this automatic control of governor 45 is thus applied to all of the units T' and T'' the hand control motion of hand wheel 70 is always in gear, so that at any time an operator at a unit T'' may superpose the hand control motion on all other controlled motions which are in progress. It is thus possible to shut down the unit by hand at any time, as in case of emergency, without first disconnecting any other mechanism and it is also possible to adjust the valves 63 of various units with relation to each other so as to proportion the load in any desired manner.

The effect of the interconnecting mechanism is always to cause the gates of all the secondary units to follow up, and approach the position corresponding to that taken by the gate of the primary governed unit due to the load change. After the first shift of the primary gates to take up practically the entire load change at a relatively rapid rate the effect will be for the primary unit gradually to unload a part of the load change upon the other units, until only its own proper share remains with the primary unit, that is, the secondary units will gradually take up a part of the load change and relieve the primary unit until all the gates approach the same position leaving the plant with a load then divided equally as desired among all the units. All quick fluctuations are taken by the primary unit and then the load is slowly distributed over the entire station. If the load change is an increase in load the first unit will take the increase, its gate quickly opening so as to maintain as nearly as possible a constant speed in this unit and the alternating current generators of each secondary unit automatically remaining in step with the primary unit. The gates of the secondary units will then begin slowly to open and the gate of the primary unit will slowly close until all the gates have reached an equilibrium as set by their respective governing valves.

As a further means of controlling each unit T'' an electric motor 72 may be provided (Fig. 6) contained within the base of the control stand h and connected through a worm 73 and worm wheel 74 and long faced pinion 75 to a gear 76 mounted on the vertical restoring rod 59 at the left end of the floating lever 58. This gear 76 rotates a nut engaging a screw on the restoring rod so that by operating the motor the floating lever 58 may be raised or lowered and the valve 63 correspondingly moved. This motor 72 furnishes a remote control means by which the turbine may be operated from the switchboard or other convenient location. This remote control mechanism therefore, like the hand control mechanism, is always in gear and it is not possible for an operator to leave it disconnected. The motor 72 may be arranged to operate directly on the valve spindle or stem 62 instead of upon the restoring rod 59, the effect being the same in either case.

Although with very few exceptions hydroelectric units are built so as to be safe at runaway speed when operating at normal or full gate without load, nevertheless it is desirable, particularly in large units, sometimes to provide a safety device to prevent runaways. In the secondary units t , T'' of this system, it will often be desirable to provide a speed limiting device to take care of emergency conditions such as would exist if a generator should by any means be thrown out of syn-

chronism with the rest of the system. One means of providing such speed limitation is shown in Fig. 7 and comprises a simple form of governor head 78 contained in a casing 79 which can be bolted at any convenient point such as on the wall of the turbine pit below the generator. The pulley 80 shown at the bottom of the governor casing is belted to the main shaft of the turbine by a short connection 81. In some installations this small centrifugal governor could be conveniently mounted on a bracket connected to the turbine guide bearing close to the turbine shaft. The upper portion 82 of the casing 79 contains a hydraulic valve having a small amount of lap to prevent leakage when in its closed position. Upon a predetermined rise in speed the centrifugal governor head 78 will engage the rod 83 to open the valve of casing 82 and admit pressure from pipe 84 to pipe 85 connected to the cylinder 86 in the lower portion of the main control stand $\frac{1}{4}$ of the turbine. Pressure in this cylinder 86 will lift the piston 87, rod 88 of which is the spindle 62 of the control valve 63 and this valve will be pushed up to the limit of its travel so as to close the turbine gates and shut down the unit. To accommodate this hydraulic operation of the control valve the floating lever 58' is arranged at the top of the stand with the restoring rod 59' extending up to its left end and the controlling rod 57' divided into relatively shiftable portions by a resilient connection 89. The hand wheel 90 is provided for hand control of the valve 63 and the gear 91 keyed to the upper end of the valve 63 is adapted to be driven by an electric motor for remote electric control of the valve 63 as turning of this gear and valve will shift the valve on its spindle 62-87. During normal operation and when the speed-limiting device of Fig. 7 is not in action, cylinder 86 and piston 87 act as a dash-pot for the purpose of controlling the rapidity of the gate motion of the units under secondary control. This method of controlling the rate of gate motion of these units by dash-pot can be used, when desired, in place of the method of limiting the speed previously mentioned, namely, by the use of restricted valve ports and piping. The dash-pot has the advantage of making the time adjustable by means of the adjustable bypass valve through the piston 87, as shown in Fig. 8.

In installations made in accordance with the system of this invention it will generally be desirable to place the primarily governed units near the middle of the station with the secondary control units on each side thus minimizing the length of interconnecting mechanism. In some plants where there is difficulty in arranging for the mechanical interconnecting mechanism a fluid transmission could be substituted in whole or in part. Such fluid transmission would comprise a diaphragm or

a piston and oil piping to a second diaphragm forming a closed system to transmit the motion of the gates and restoring mechanism between the primary and secondary units as shown at 84, 85, 86 and 87 in Figs. 7 and 8, 70 a means being provided for making up any loss of oil.

In power stations as heretofore arranged with separate governor on each unit, it has been necessary in order to provide a means 75 for automatically distributing the load among the various units in the station to adjust the secondary compensation in such a way that the speed of a unit is automatically adjusted to a different value for each degree 80 of gate opening. Although in many governors so arranged, the adjustment may be so made that the drop in speed from no-load to full-load is a very small percentage of the normal speed, it is not possible to permit this 85 restoration to bring the speed to a constant value for all gate openings without sacrificing the automatic distribution of load among the units. In other words, in the usual system, the governors cannot be made to give 90 isochronous adjustment after they have completed the action upon any change of load. In the system of this invention, however, the interconnecting mechanism performs the function of distributing the load among the 95 units, and it becomes possible to adjust the secondary compensation so that after the governing action is completed, the speed is returned to a constant value or very close to such value; thus this system provides a 100 method of substantially isochronous governing.

While different forms of the invention have been shown it will of course be understood that other forms and changes in details and arrangement of parts may be made without departing from the spirit of the invention as set forth in the appended claims.

I claim:

1. The combination with a hydraulic turbine unit having control gate means and driving an alternating current synchronous generator, of regulating means therefor comprising a control valve, means for moving said valve including restoring mechanism 110 between the gates and said valve and a remote control mechanism and a hand operated mechanism, all of said mechanisms being adapted for simultaneous operation without disconnecting any one of them, at least one additional hydraulic turbine unit driving a synchronous generator in parallel with said other unit, and a governor responsive to the speed of said additional unit or units for controlling the same. 120

2. The combination with a hydraulic turbine unit having control gate means and driving an alternating current synchronous generator, of regulating means therefor comprising a control valve, means for moving 130

5 said valve including restoring mechanism between the gates and said valve and a remote control mechanism and a hand operated mechanism, all of said mechanism being
 10 adapted for simultaneous operation without disconnecting any one of them, at least one additional hydraulic turbine unit driving a synchronous generator in parallel with said other unit, a governor responsive to the speed of said additional unit or units for controlling the same, and means whereby said remote control mechanism is adapted to distribute the load among all of the units in any desired proportions.

15 3. In a power generating system, the combination comprising a plurality of prime mover operated alternating current synchronous generating units, each adapted to carry a part of the total load on said system, a unitary governor control adapted to control the frequency of said system by acting on less than all of said units, means whereby the system load is proportionately distributed over a plurality of the system units automatically upon variations in the system load, and remote control mechanism on at least one of the governorless units adapted to vary the proportioning of load between said units.

20 4. In a hydraulic power system the combination with a synchronous generator turbine unit of a regulating means therefor comprising a governor responsive to the speed of said unit, a valve controlled by said governor, and means for independently adjusting said valve without disconnecting said governor control comprising power means for moving said valve, means for controlling said power means from a remote point, at least one other unit driving a synchronous 25 generator connected in parallel with the first unit, and remote control means for distributing in predetermined proportions the system load among all of said units.

30 5. Governing apparatus for a hydraulic turbine having a fluid control element for the flow to said turbine and fluid pressure operating means therefor comprising a main control valve and a pilot valve therefor, a governor proper, a restoring mechanism acting directly on the main valve, and a secondary compensating mechanism controlling the motion of the pilot valve.

35 6. In a power system, the combination comprising a plurality of hydraulic turbine units each having gate mechanism and a fluid-pressure operated motor for moving the same and each motor being provided with a control valve, an automatic speed governor for one of said units, and means for effecting relatively quick turbine gate control when the system load changes and then subsequently effecting further turbine gate control to redistribute the system load in a predetermined ratio between a plurality of the units, said means including interconnecting means

between said governor and each of said control valves whereby the speeds and loads of a plurality of said units are controlled.

7. In a hydraulic power system the combination with a plurality of hydraulic turbine units, each having gate mechanism and a hydraulically operated motor for moving the same, and each motor having a control valve, of an automatic speed governing means for certain of said units, connecting means between said governing means and each of said control valves whereby said governing means controls the speeds of a plurality of said units, and means whereby each unit is adapted to have a relatively quick primary restoring action and a relatively slow secondary restoring action.

8. In a hydraulic power system the combination with a plurality of hydraulic turbine units each having gate mechanism and a hydraulically operated motor for moving the same, a control valve associated with each motor, and a primary restoring mechanism between each motor and its control valve, each of said primary compensating mechanisms being adapted to effect its compensating action independently of the others, and means for effecting a secondary restoring action simultaneously on each unit, of an automatic speed governor for one of said units comprising a valve actuating member, and connecting means between the valve actuating member of said governor and the control valves of said units whereby said governor controls the speeds of a plurality of said units.

9. In a hydraulic power system the combination with a plurality of hydraulic turbine units, of an automatic speed governor, fluid pressure operated gates for each of said units, valves for controlling the fluid pressure for operating said gates, a restoring mechanism associated with each of said gate operating mechanisms whereby each gate mechanism may have a certain amount of independent movement, means for effecting a secondary compensating action on each turbine unit, and means connecting said governor to said valves whereby said governor controls the speed of all of said units.

10. In a hydro-electric alternating current power system, the combination comprising a plurality of synchronous generators operating in parallel and driven by hydraulic turbines having different operating characteristics, each of said turbines having a gate mechanism, a control valve and restoring mechanism, and governing means operative to effect actuation of each of said control valves and permit relative movement therebetween thereby effecting gate control to regulate the turbine speed and accordingly the system frequency, said governing means including interconnecting means between the units for controlling the gate mechanism au-

- tomatically in accordance with said operating characteristics so as to redistribute the system load between the units in a predetermined ratio when the system load changes.
- 5 11. In a hydro-electric alternating current power system, the combination comprising a plurality of hydraulic turbine operated synchronous generators, fluid pressure operated gates for said units having restoring mechanism associated with each gate, valves for controlling the fluid pressure operation of said gates, speed responsive governing means for controlling said valves, and interconnecting means between all of said units 10 for effecting gate adjustment automatically in accordance with a predetermined ratio of redistribution of the system load among the units after a change in the system load while all units operate at a common speed.
- 15 12. In a power system, the combination comprising a plurality of prime mover operated synchronous generators connected to a common alternating current circuit, each prime mover having valve mechanism for controlling the prime mover motive fluid, governing means for effecting relatively quick control of the frequency by effecting relatively quick valve movement, and interconnecting means, independent of said alternating current circuit, between all of said units for redistributing in a predetermined ratio the system load among the units by effecting relatively slow valve movement after said quick movement.
- 20 13. In a hydraulic power system the combination with a plurality of turbine units each having gates, operating means therefor, and restoring mechanism, of automatic speed governors for at least two of said units, and interconnecting mechanism for interchangeably operating a unit either under the control of its own governor or in common with another unit under the simultaneous control of the governor of said other unit, the restoring mechanisms for each unit being adapted to permit a certain amount of restoring action on each unit independently of one another or upon the governor control which is in operation.
- 25 14. In a hydraulic power system the combination with a plurality of turbine units each having gates, operating means therefor, and restoring mechanism, of automatic speed governors for at least two of said units, and interconnecting mechanism for interchangeably operating a unit either under the control of its own governor or in common with another unit under the simultaneous control of the governor of said other unit or under the sole control of said other governor, the restoring mechanisms for each unit being adapted to permit a certain amount of restoring action on each unit independently of one another or upon the governor control which is in operation.
- 30 15. In a power system the combination with a plurality of hydraulic turbine units each having a gate mechanism and an operating motor provided with a control valve, of an automatic speed governor responsive to the speed of one of said units, connecting means between said governor and said control valves whereby said governor controls the speeds of a plurality of said units, restoring mechanism associated with each of said control valves whereby restoring action of one valve may be had independently of the others and a hand control for effecting operation of certain of said control valves independently of the governor.
- 35 16. In a hydraulic power system the combination with a plurality of hydraulic turbine units each having a gate mechanism and an operating motor provided with a control valve, of automatic speed governing means for certain of said units, connecting means between said governing means and said control valves whereby said governing means controls the speeds of a plurality of said units, restoring mechanism associated with each of said control valves whereby restoring action of one valve may be had independently of the others and a hand control for effecting operation of certain of said control valves independently of the governor.
- 40 17. In a power system the combination with a plurality of hydraulic turbine units each having a gate mechanism and an operating motor provided with a control valve, of an automatic speed governor responsive to the speed of one of said units, connecting means between said governor and said control valves whereby said governor controls the speeds of a plurality of said units, restoring mechanism associated with each of said control valves whereby restoring action of one valve may be had independently of the others, and means for further controlling certain of said control valves including an independent hand control adapted for simultaneous operation with said governor control.
- 45 18. In a hydraulic power system the combination with a plurality of hydraulic turbine units each having a gate mechanism and an operating motor provided with a control valve, of automatic speed governing means for certain of said units, connecting means between said governing means and said control valves whereby said governing means controls the speeds of a plurality of said units, restoring mechanism associated with each of said control valves whereby restoring action of one valve may be had independently of the others, and means for further controlling certain of said control valves including an independent hand control adapted for simultaneous operation with said governor control.
- 50 19. In a governing system for a hydraulic turbine the combination with gate mechanism and a fluid pressure motor for moving

- the same, of a distributing control valve for the motor actuating fluid, means for automatically governing said control valve including a governor controlled pilot valve, and 5 means for independently regulating said distributing control valve by hand during operation by said automatic governing means.
20. In a governing system for a hydraulic turbine, the combination with a gate mechanism and a fluid operated motor therefor, of a distributing control valve for the motor actuating fluid, and means including an automatic governor for moving said valve and a pilot valve controlled by said automatic 10 governor, and hand controlled means for superposing upon the motion received from the governor a second regulating or adjusting motion.
21. In a hydraulic power system, the combination with a turbine unit, of a distributing control valve therefor, means including a governor and a governor controlled pilot valve for moving said distributing valve, hand controlled means for moving said distributing valve, and means for moving said distributing valve by remote control, the motion of said valve being the aggregate of all the said motions.
22. In a hydro-electric power system, the combination comprising a plurality of hydraulic turbine operated synchronous generators connected to a common alternating current circuit and each turbine having a gate mechanism, governing means for effecting 30 quick control of the frequency by relatively quickly moving the gates on at least one of said units, and interconnecting means between all of said units, for effecting relatively slow gate adjustment after said quick 35 movement automatically in accordance with a predetermined ratio of redistribution of the system load among the units.
23. In a power system, the combination comprising a plurality of hydraulic turbine units each having gate mechanism and a fluid pressure operating motor provided with a control valve, an automatic speed governor for one of said units, and connecting means, including restoring mechanism, between said 40 governor and each of said control valves adapted to permit relative movement between the control valves of said units while said governor controls the speed of a plurality of said units.
24. In a hydro-electric power system, the combination comprising a plurality of hydraulic turbine operated synchronous generators connected to a common altering current circuit, certain of said units having movable guide vanes and other of said units having only fixed guide vanes, a governor for effecting relatively quick movement of said movable guide vanes during any changes in the system load, relatively slowly movable flow controlling means in the units having 45 the fixed guide vanes, and means operatively associated with said governor for controlling said slowly movable flow controlling means.
25. In a hydraulic power system the combination with a synchronous generator turbine unit of a regulating means therefor comprising a governor responsive to the speed of said unit, a valve controlled by said governor, and means for independently adjusting said valve without disconnecting said governor 70 control comprising power means for moving said valve, means for controlling said power means from a remote point, at least one other unit driving a synchronous generator connected in parallel with the first unit, and means for distributing in predetermined proportions the system load among all of said units upon variation in response to system load changes.
26. In a hydraulic power system the combination with a plurality of hydraulic turbine units each having gate mechanism and a fluid operated motor therefor provided with a control valve, of a unitary governing 75 mechanism for said control valves of all of said units, and means for relatively varying the rate of regulation of some of said units.
27. In a hydraulic power system the combination with a unitary control system, of turbine units equipped with two different types of control gates having different rates of operation so that a given load change will be taken up relatively quickly by the gates of one type and relatively slowly by those of the other type.
28. In a hydraulic power system the combination with a plurality of turbine units adapted for approximately similar rates of regulation, of one or more turbine units adapted for a different rate of regulation, and governing means in common between all 80 of said units.
29. In a hydraulic power system the combination with a unitary control system, of a plurality of turbine units having different rates of regulation so that a given load change will be taken up relatively quickly by certain of said units and relatively slowly by others.
30. In a hydraulic power system the combination with a unitary control system, of a plurality of turbine units of different types having different rates of regulation so that a given load change will be taken up relatively quickly by certain of said units and relatively slowly by others.
31. In a hydraulic power system the combination with a hydraulic turbine structure of the reaction type, of regulating means relatively quickly responsive to changes of load, regulating means relatively slowly responsive to changes of load, and interconnecting mechanism between said regulating means to control one by the other.
32. In a hydraulic power system the com-

- bination with a plurality of turbine units of the reaction type, of regulating means relatively quickly responsive to changes of load, regulating means relatively slowly responsive to changes of load, and interconnecting mechanism between said regulating means to control one by the other.
33. In a hydraulic power system the combination with a turbine unit having an automatic speed governor, of one or more other turbine units having hand control mechanism, interconnecting means whereby said automatic speed governor controls all of said units, and means for effecting primary restoring action and secondary compensating action on each unit.
34. In a hydraulic power system the combination with a turbine unit having an automatic speed governor, of one or more other turbine units having hand control mechanism, mechanical interconnecting means between said governor and said mechanism whereby said automatic speed governor controls all of said units, means for effecting primary and secondary compensating action on each unit.
35. The combination with a hydraulic turbine installation of the reaction type, of regulating means therefor comprising a primary flow control means relatively quickly responsive to load changes and a secondary flow control means relatively slowly responsive to load changes and unitary governing means for both of said flow control means.
36. The combination with a hydraulic turbine installation of the reaction type, of regulating means therefor comprising a primary flow control mechanism relatively quickly responsive to load changes and a secondary flow control mechanism relatively slowly responsive to load changes and unitary governing means for said mechanisms adapted to shift said primary mechanism to take a load change and then to distribute the load change between said primary and secondary mechanisms.
37. In a hydraulic power system the combination with a turbine unit having water passages of large cross section and a control means adapted for quick regulation, of one or more other turbine units having water passages of relatively small cross section and control means adapted for slow regulation, and a unitary governing system for all of said units.
38. The combination with a hydraulic turbine unit having a gate mechanism and an operating motor therefor provided with a control valve of regulating means for said control valve comprising a hand control, and a remote control for said valve comprising means for moving said valve from a distance, either of said means being capable of simultaneously controlling the valve without disconnecting the other means.
39. The combination with a hydraulic turbine unit having control gate means, of regulating means therefor comprising a control valve, and means for moving said valve including restoring mechanism between the gates and said valve and a remote control mechanism and a hand operated mechanism, all of said mechanisms being adapted for simultaneous operation without disconnecting any one of them.
40. In a hydraulic reaction turbine, regulating means therefor comprising a primary flow control means relatively quickly responsive to load changes and a secondary flow control means relatively slowly responsive to load changes and unitary governing means for both of said flow control means.
41. In a power system the combination comprising a plurality of hydraulic turbines each driving an alternating current synchronous generator, each turbine having a gate mechanism and a fluid operated motor therefor provided with a control valve, means for effecting primary restoring action on the valve of each turbine, secondary compensating mechanism for each of said valves, said synchronous generators being connected to run in parallel with each other, an automatic speed governor for one of said turbines, and connecting means between said governor and said control valves whereby said governor controls the speeds of a plurality of said turbines while the speed on said turbines is maintained the same by said parallel operation during variations in the rate of restoring action on each turbine.
42. In a power system the combination comprising a plurality of hydraulic turbines each driving an alternating current synchronous generator, said generators being connected to run in parallel with each other, each turbine having a gate mechanism and a hydraulically operated piston and cylinder motor provided with a control valve, means for effecting primary restoring action on the control valve of each turbine, secondary compensating mechanism for each of said valves, an automatic speed governor for certain of said turbines, and connecting means between said governor and said control valves whereby said governor controls the speeds of a plurality of said turbines.
43. In a hydraulic power system the combination comprising a plurality of hydraulic turbines each driving an alternating current synchronous generator, said generators being connected to run in parallel with each other, each turbine having a gate mechanism and a hydraulically operated piston and cylinder motor provided with a control valve and a restoring mechanism, an automatic speed governor for one of said turbines comprising a valve actuating member, and connecting means between the valve actuating member of said governor and said control valves.

whereby said governor controls the speeds of a plurality of said turbines.

44. A hydraulic power system comprising a plurality of turbines driving alternating current synchronous generators running in parallel, one or more of said turbines having water passages of relatively large cross section to and from said turbine and having automatic governing and control means adapted for quick regulation, and one or more of said turbines having water passages of relatively small cross section and control means adapted for slow regulation and inter-connected to said first mentioned means.

45. In a power system the combination with a plurality of hydraulic turbines each driving an alternating current synchronous generator, each turbine having a gate mechanism and a hydraulically operated piston and cylinder motor provided with a control valve and restoring mechanism, said generators being connected to run in parallel with each other, of an automatic speed governor for one of said turbines, means whereby all of said turbines have operative connection with said speed governor, and speed regulating mechanism for another of said turbines adapted to limit the speed of said other turbine independently of the speed of said automatically governed turbine.

46. The combination comprising a plurality of hydraulic turbine units each having regulating means comprising gate mechanism and an operating motor therefor provided with a control valve, of a governor for each of said units, and means for connecting the governor of one unit to the regulating means of another unit so that said governor will regulate both units, said connecting means including means whereby the gates of one unit move at a rate different from the gates of another unit.

47. In a hydraulic power system the combination with a plurality of turbine units, of a unitary control system comprising a governor responsive to the speed of one of said units, and means whereby control of the gate means of all of said units may be had so that a given load change will be taken up relatively quickly by certain of said units and relatively slowly by others.

48. Governing apparatus for a hydraulic turbine which has associated therewith a fluid control element for the flow to said turbine and operating means for said control element, said apparatus comprising a governor proper, means including a valve controlled by said governor for effecting actuation of said operating means, a primary restoring mechanism separate from the governor proper and having relatively short connections between said operating means and said governor control adjacent said valve, and a secondary compensating means operative only when said governor operates and

at the governor proper acting to bring the speed of the turbine back to normal.

49. In a hydraulic power system the combination comprising a plurality of hydraulic turbine units, a unitary governing mechanism for all of said units each of which has a gate mechanism and a fluid operated motor therefor provided with a control valve, restoring mechanism for each of said control valves, and means relatively varying the rate of regulation of some of said units comprising a hand adjustment of portions of said unitary governing mechanism.

50. In a hydraulic power system the combination with a plurality of hydraulic turbine units each having a gate mechanism and a fluid operated motor therefor provided with a control valve, of a unitary governing mechanism for all of said units comprising a primary restoring mechanism for each of said units and means for effecting a secondary compensating action on each unit, and means relatively varying the rate of regulation of some of said units comprising adjusting means for said restoring mechanism.

51. In a power system the combination with a plurality of hydraulic turbines each driving an alternating current synchronous generator, said generators being connected to run in parallel with each other, of an automatic speed governor for one of said turbines, means whereby all of said turbines have operative connection with said speed governor, and speed regulating mechanism for another of said turbines adapted to limit the speed of said other turbine independently of the speed of said automatically governed turbine comprising a centrifugally operated element adapted to automatically cause a closing movement of the gates when a predetermined speed is reached.

52. In a hydraulic power system the combination with a plurality of turbine units adapted for approximately similar rates of regulation, each unit including a gate mechanism and a hydraulically operated servo-motor therefor provided with a control valve, of one or more turbine units adapted for a different rate of regulation, and governing means in common between all of said units and adapted to control said servo-motor valves.

53. In a hydraulic power system the combination with a plurality of turbine units adapted for approximately similar rates of regulation, each unit including a gate mechanism and a servo-motor therefor, of one or more turbine units adapted for a different rate of regulation, and governing means in common between all of said units for controlling power supply to said servo-motors.

54. In a hydraulic power system the combination with a plurality of turbine units adapted for approximately similar rates of regulation, of one or more turbine units

adapted for a different rate of regulation, and governing means in common between all of said units including a valve controlled servo-motor associated with each unit, and compensating mechanism for said valve.

5. 55. In a hydraulic power system the combination with a plurality of turbine units adapted for approximately similar rates of regulation, of one or more turbine units adapted for a different rate of regulation, governing means in common between all of said units including a valve controlled servo-motor associated with each unit, a compensating mechanism for said valve rendered operative upon movement of the servo-motor, and a second compensating mechanism rendered operative only after an initial governing action.

20 56. In a hydraulic power system the combination with a plurality of turbine units adapted for approximately similar rates of regulation, of one or more turbine units adapted for a different rate of regulation, governing means in common between all of said units including a valve controlled servo-motor associated with each unit, compensating mechanism for said valve rendered operative upon movement of the servo-motor, and a second compensating mechanism associated 25 with only one of said turbines but adapted 30 to effect control of all.

57. In a hydraulic power system the combination with a unitary control system, of a plurality of turbine units having means permitting different rates of regulation so that a given load change will be taken up relatively quickly by certain of said units and relatively slowly by others, including a gate mechanism and an operating motor therefor 40 associated with each turbine, and means for controlling the rate of power supply to each of said operating motors.

45 58. In a hydraulic power system the combination with a unitary control system, of a plurality of turbine units having means permitting different rates of regulation so that a given load change will be taken up relatively quickly by certain of said units and relatively slowly by others, including a gate mechanism and an operating motor therefor 50 associated with each turbine, and means for controlling the rate of power supply to each of said operating motors, said latter means including means forming fluid conducting 55 passages having different cross-sectional areas whereby different rates of fluid flow are obtained.

60 59. The combination comprising a hydraulic turbine, having gate mechanism, actuating means therefor and means for controlling said actuating means including a plurality of governors, and means for averaging the motions thereof.

65 60. A hydraulic power system comprising,

in combination, hydraulic power generating means having means adapted to effect quick regulation thereof, hydraulic power generating means having means adapted to effect slow regulation thereof, means whereby all of said power generating means are maintained in synchronous driving relation and means for limiting the speed of said power generating means rendered operative only by a speed change exceeding a predetermined amount.

61. In a power generating system, the combination comprising a plurality of prime mover operated alternating current synchronous generating units operating in parallel, each being adapted to carry a part of the total load on said system, a governor controlled unit adapted to control the frequency of said system, and means for distributing in predetermined proportions the system load over a plurality of said units automatically during variations in the system load.

62. In a power generating system, the combination comprising a plurality of prime mover operated alternating current synchronous generating units, each being adapted to carry a part of the total load on said system, unitary control means adapted to control the frequency of said system through a single generating unit and to distribute in predetermined proportions the load among all of said units automatically upon variation in the system load.

63. In a power generating system, the combination comprising a plurality of prime mover operated alternating current synchronous generating units, each adapted to carry a part of the total load on said system, a unitary governor control adapted to control the frequency of said system by acting on less than all of said units, and means whereby the system load is proportionately distributed over a plurality of the system units automatically upon variations in the system load.

64. The combination as set forth in claim 63 further characterized in that a plurality of said prime movers have movable flow controlling means, each of said flow controlling means being provided with a governor controlled valve, and restoring mechanism for said valves, responsive to movement of said flow controlling means, with provision whereby each unit is adapted to have restoring action independently of the restoring action on the other units.

65. The combination as set forth in claim 63 further characterized in that a plurality of said prime movers have movable flow controlling means, each of said flow controlling means being provided with a governor controlled valve, and restoring mechanism for said valves, responsive to movement of said flow controlling means, with provision whereby each unit is adapted to have restoring action independently of the restoring action on

the other units, and secondary compensating means for the valves of each unit.

66. In a hydraulic power alternating current generating system, the combination comprising a plurality of hydraulic turbine operated alternating current synchronous generating units each having a gate mechanism, governing means for effecting quick control of frequency by relatively quickly moving the gates on less than all of said units, and means on the remaining units for relatively slowly adjusting the gates thereby to redistribute the system load among the units.

LEWIS FERRY MOODY.

CERTIFICATE OF CORRECTION.

Patent No. 1,836,861.

Granted December 15, 1931, to

LEWIS FERRY MOODY.

It is hereby certified that error appears in the printed specification of the above numbered patent requiring correction as follows: Page 2, line 3, for the word "grates" read gates; page 7, lines 82 and 93, claims 7 and 8, respectively, for "restoring" read compensating, and in claim 8, lines 90 and 91, for "compensating" read restoring; page 9, line 27, claim 21, before "valve" insert distributing, and line 58, claim 24, for the misspelled word "alterating" read alternating; page 10, line 24, claim 34, before "means" insert and; page 11, line 75, claim 49, after "means" insert the word for; and that the said Letters Patent should be read with these corrections therein that the same may conform to the record of the case in the Patent Office.

Signed and sealed this 22nd day of March, A. D. 1932.
